(57) **CLAIM**

I claim the ornamental design for a tree made from record albums, as shown and described.

DESCRIPTION

FIG. 1 is a perspective view of a tree made from record albums, showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The broken lines showing the netting in FIGS. 1-5 and the interior base with netting of FIG. 7 illustrates environmental subject matter that forms no part of the claimed design.
